UNITED STATES PATENT OFFICE

2,158,479

DISTRIBUTOR FOR FERTILIZER, LIME, OR
THE LIKELorenzo Dow Pender, Raleigh, N. C., assignor to
Ruth McW. Pender, Raleigh, N. C.

Application February 8, 1937, Serial No. 124,771

1 Claim. (Cl. 221—118)

This invention relates to a distributor for fertilizer, lime or the like and it is designed primarily as an improvement upon the structure disclosed in Patent 1,840,602, issued to me on January 12, 1932.

In the patent herein referred to it is possible to close selected outlets in the bottom of a hopper, attach delivery spouts to the remaining or unclosed outlets, and thereby deliver fertilizer, lime or the like, in rows spaced apart predetermined distances. It has been found in practice, however, that when only a small portion of the bottom is left open, the undischarged portion of the material left in the hopper, being in constant agitation, sets up an excessive resistance to the movement of the machine, thereby making it harder to pull. It has also been found that this constant agitation of undischarged material tends, more particularly in damp weather or when the material itself is damp, to reduce the undischarged material to a sticky, paste-like condition which tends to pack and cause trouble.

An object of the present invention is to avoid the objections herein enumerated by providing a machine which, while adjustable for the purpose of delivering material either broadcast or in bands or streams any desired distances apart, will nevertheless reduce the resistance heretofore encountered and also avoid the undesirable packing referred to.

A further object is to provide the interior of the hopper containing the material to be distributed so that it will consist of separate compartments arranged side by side each of which contains an agitator and also is provided with one or more outlets and with a lid whereby material can be prevented from discharging into any of these compartments or, if discharged thereinto, will be agitated and properly delivered through the outlet.

A further object is to so locate the lids or covers of the closed compartments that material discharged into the hopper and deposited on these lids, can be brushed readily into the adjacent open compartment so that it will not pile or pack between unused outlets as heretofore.

With the foregoing and other objects in view which will appear as the description proceeds, the invention consists of certain novel details of construction and combinations of parts herein-after more fully described and pointed out in the claim, it being understood that changes may be made in the construction and arrangement of parts without departing from the spirit of the invention as claimed.

In the accompanying drawings the preferred form of the invention has been shown.

In said drawings

Figure 1 is a view partly in rear elevation and partly in section of a distributor constructed in accordance with the present invention.

Figure 2 is a top plan view thereof.

Figure 3 is an enlarged vertical transverse section through the hopper, said section being taken on line 3—3, Figure 4.

Figure 4 is a longitudinal section through a portion of the hopper taken on line 4—4, Figure 3.

Referring to the figures by characters of reference 1 designates a hopper which can be of such length as to extend over two or more rows. A 15 rotatable axle 2 is journalled in the ends of this hopper and also within one or more intermediate bearings 3 and the ends of this axle are supported by wheels 4. Any desired means can be employed for pulling the machine. For example tongues or 20 shafts 5 can be secured on the hopper and extended forwardly therefrom for attachment to a draft animal.

Secured within the lower portion of the hopper are parallel partitions 6 which divide the lower 25 portion of the hopper into separate compartments 7. Each of these compartments has a desired number of outlets 8 in the bottom thereof and all of the outlets of the several compartments are aligned longitudinally of the hopper. Guides 9 30 are secured to the bottom of the hopper between the outlets and serve to support separately removable closure plates 10 or, in lieu thereof, plates 11 from which spouts 12 depend, these plates 11 having openings through which material can flow 35 into the spouts.

Secured to the rotatable axle 2 and located within each of the compartments 7 is an agitator 13 of any desired construction. As shown in the drawings this agitator can be made up of arms 14 40 radiating from hubs 15 which are secured to the axle 2, the outer ends of the arms being joined by connecting strips or blades 16. Thus when the axle rotates as the machine is moved forwardly, these agitators will also rotate within their respective compartments and keep the contents of the compartments in motion so that the outlets 8 will not become choked.

Secured to opposed faces of each partition 6 and extending above the upper edge of the partitions, are parallel strips 17 cooperating with the partitions to form channels which open upwardly. Offset strips 18 are secured to the end walls of the hopper to provide channels between said walls 55

and the strips, these channels opening upwardly as shown particularly in Figure 4.

Normally resting on the strips 17 and 18 are lids 19 each of which is formed preferably of a metal plate the side edges of which are down-turned as shown at 20 so as to fit within the channels while the front and back edges thereof are upturned as at 21, the angles of these upturned portions being such as to cause them to lie flush upon the downwardly converging front and back walls of the hopper. Thus when all of the lids are in place, all of the compartments 7 will be closed and the lids will form a false bottom constituting the bottom of an upper compartment. 15 Thus any fertilizer, lime or other material deposited in the upper portion of the hopper 1 will be supported on these lids. The upper compartment is free from rods, wires or other obstructions which might interfere with the free movement of the bulk material over any of the lids toward one or more outlets should other lids be removed.

For the purpose of fastening the lids in closed position, holding plates 22 are mounted on the inclined front and back walls of the hopper, these plates being formed with slots 23 through which extend bolts 24. The plates can be allowed to gravitate downwardly onto the lids 19 as shown in Figure 3 or, if preferred, could be caused to 30 gavitate against the upper edges of the portions 21 of the lids. In either case, the plates, when fastened by tightening the bolts 24, will hold the lids against removal or accidental displacement. For the purpose of removing a lid, the bolts 35 en-gaging plates 22 used for fastening the lids in position, are loosened and said plates 22 are slid upwardly out of the path of the lid so that said lid thus can be lifted out of place. It will be noted that each of the plates 22 positioned over partitions 40 6 serves to hold two lids in place. See Figure 4.

In practice plates 10 are removed from under those outlets 8 from which material is to be delivered and plates 11 are substituted therefor, 45 these latter plates being provided with the depending spouts 12 which can be made flexible so as to be extended laterally to deliver material at desired points. If the outlets at the bottom of any of the compartments 7 are left closed, the lids 19 over said compartments are left in closed positions thereby to form a sectional false bottom 50 for the hopper. The lids over the compartments having open outlets are removed, however. In

Figures 1 and 2 the end compartments 7 and the central compartment have been shown open with spouts depending from the bottoms thereof while the remaining compartments 7 have been shown closed both at their tops and at their outlets. 5

Fertilizer, lime or other material to be distributed is delivered into the hopper 1. Some of this material will enter the open compartments 7 but the remaining material which ordinarily would remain unused in the area between the 10 depending spouts, will be supported instead within the upper portion of the hopper and upon the lid of the closed compartment. Thus only those portions of the material to be delivered will be agitated and, consequently, the draft upon the 15 machine will be reduced materially. The unused portions of material resting on the lids of the closed compartments will be left undisturbed until one or more of the open compartments become empty whereupon the operator can brush portions of the material from the lids of the closed compartments laterally into the open compartment. 20

It is to be understood of course that it is not always necessary to use the delivery spout. Instead the material can be broadcast by falling directly from the outlets. Under any condition, however, the provision of the separate compartments with their separately removable lids and with their outlets any of which can be opened or 25 closed as desired, provide a very effective means for controlling the distribution of material from the hopper, reducing the load upon the draft animal, and permitting the utilization of all of the material without encountering those difficulties present where the material is subjected to constant agitation or churning while located at 30 points remote from the outlets. 35

What is claimed is:

A distributor for fertilizer or the like including 40 a hopper having parallel partitions dividing the lower portion of the hopper into separate compartments each having an outlet, a closure for each outlet, separately removable lids for the compartments cooperating to form a sectional 45 false bottom for the hopper, means on the lids for engagement with the upper portions of the respective partitions, means on the respective lids for engaging the adjacent walls of the hopper, and means for fastening the respective lids into 50 position on said partitions and walls.

LORENZO DOW PENDER.
